MILK BOTTLE HOLDER

Horton D. Cole, Scotia, N. Y.

Application February 16, 1937, Serial No. 126,086

4 Claims. (Cl. 232—41)

This invention relates to a multiple milk bottle holder preferably of the home or domestic type and classifiable as pertaining to that line of endeavor having to do with the so-called automatic dispensing or vending bottle holder.

More specifically, and indicated along structural lines, the preferred embodiment of the invention is characterized by a box or similar inclosure having therein novel bottle racking and vending means of a type wherein, in order to remove a full bottle of milk, it is necessary to first insert an empty bottle.

As implied by the preceding paragraphs, it is evident that I am reasonably well conversant with the general state of the art to which the invention relates and have therefore set about to generally improve upon these appreciably old arrangements by providing a comparatively new structure wherein the essential novelty is predicated upon the so-called bottle racking and dispensing means, and more in particular on the mechanism embodied in said means for controlling the insertion and removal of empty and full bottles.

25 Inasmuch as the objects, features, and advantages of the invention are primarily of a structural nature, the succeeding description will be so prepared as to bring these out in a systematic and progressive manner.

30 In the accompanying drawings, wherein like numerals are employed to designate like parts throughout the various views:

Figure 1 is a sectional view, that is, what may be called a central vertical section through the preferred embodiment of the invention, showing, in dotted lines, the general method of using the structure, and depicting in detail the outstanding features of the invention.

Figure 2 is an end view of Figure 1, that is, a view looking at it in a direction from right to left, with the hinged closing door removed for clarity of illustration.

Figures 3 and 4 are sections on the lines 3—3 and 4—4, respectively, of Figure 1.

45 Figure 5 is a view which may be said to be taken approximately on the plane of the line 5—5 of Figure 4.

Figure 6 is a perspective view of the bottle actuated trip lifting plate or member.

50 Figures 7 and 8 are detail perspective views.

Figure 9 is an enlarged detailing section illustrating a principle of operation of said features, hereinafter clarified.

55 It is understood that the box or other inclosure utilized may be of any appropriate con-

struction. It is unitarily referred to in the drawings by the numeral 10 and is adapted to accommodate several quart size or other predetermined milk bottles. It might well be pointed out here that ordinarily it is necessary to operate this invention by three simultaneously and progressively movable milk bottles, and for this reason the bottles shown in dotted lines in Figure 1 are differentiated by the characters A, B and C. The cabinet or box is open at one end, 10 which forms the entrance, and here is a suitable hinged drop-type closing door or lid 11. At the opposite end the structure is fashioned into what may be designated as the receiving and removing compartment or chamber 12, through which 15 the bottle C is lifted and bodily removed for use. At the top of this compartment 12 is an appropriate cover or lid 13.

Mounted within the box is a multi-part metal structure which may be unitarily described as a 20 rack or holder, and this embodies a horizontal trough or channel having a bottom 14 and spaced parallel side walls or flanges 15 facilitating sliding of the bottles in a direction from right to left in Figure 1. The numerals 16 and 17 designate perpendicular longitudinally spaced pairs of uprights, and the numerals 18 and 19, seen better in Figures 2 and 3, designate stabilizing units of general U-shaped form cooperating with these uprights 16 and 17. Thus, in effect, we 25 have a pair of vertical, longitudinally spaced arched frames to support the tracks or horizontal angle irons shown in the drawings. For sake of distinction, the vertical flanges of the angle irons are denoted by the numeral 20 and 30 the horizontal flanges are indicated at 21. These are disposed in spaced parallel order to permit the bottle to ride therebetween in an evident manner.

It is evident that the primary purpose of these 40 angle irons is to support the devices which control the movement of the milk bottles. In accomplishing the desired results I have found it expedient and practicable to utilize what may be called inner and outer pairs of star-wheels, 45 the inner ones being indicated by the numerals 22 and the outer ones by the numerals 23. These are pivotally mounted on the horizontal flanges as indicated at the point 24, and are rotatably operable through clearance slots 25 and 26, respectively. The prongs or lugs formed on the star-wheels are in effect cams and the cam elements on the wheels or rotors 22 are denoted by the numeral 27, while those on the outer star-wheels are indicated at 28. It is to be ob- 50

served that the edge portions of the lugs 28 are beveled as at 29' to form properly sharpened lifting cam surfaces to be hereinafter specifically described.

The star-wheels 23 are normally locked against rotation by simple pivoted latches 29 of the type seen in Figure 8. Each latch embodies laterally bent stop elements 30 and 31, normally resting down on the edges of the vertical flanges 10 20, as shown in full lines in Figures 4 and 5. Attention is called to the numeral 32 forming a feature of the latch, and this constitutes a stop shoulder against which the lugs 28 of the star-wheels bear, as shown in Figure 5, to prevent 15 rotation of said star-wheels. Thus, before the star-wheels can rotate in opposite outward directions through the slots 26, it is necessary to lift the check latches 29. This is done by the use of a simple rectangular panel or plate 33 having 20 trunnions 34 mounted for oscillation in appropriate bearings in the upright 17, as shown to advantage in Figure 1. The plate is adapted to swing upwardly under the ears 30. It will thus be seen that as the milk bottle A is placed 25 in through the open end at the right in Figure 1, it swings the plate 33 up underneath the lifting element 30 and in turn lifts up both latches 29. Hence, when this is accomplished, the star-wheels 22 are free to rotate outwardly, that is, 30 in opposite directions, through the parts 26.

The beveled edges of the lugs on the star-wheels 23 cooperate with similar beveled or cam surfaces 35, as shown in Figures 5 and 9. The beveled edges 35 are carried on the detent or trip 35 bars 36. There are two of these bars and they are pivotally mounted as at 37 intermediate their ends on the vertical flanges of the two angle irons, as shown more satisfactorily in Figures 4 and 5. As seen to advantage in Figures 7 and 9, 40 the beveled cam surface 35 is on the substantially V-shaped lifting tooth 38 on that end of the bar 36 with which the star-wheels 23 cooperate. The opposite ends of the trip rods 36 are notched out, as indicated at 39, and further notched, as indicated at 40, to form additional stop shoulders. It follows, therefore, that when the device is 45 locked, the lugs 21 on the inner star-wheels 22 bear against the stop shoulders 40 and the rotation of said star-wheels is prevented.

50 As before indicated, and before considering the operation of the invention in detail, it is to be remembered that the invention works best when there are three bottles for use. It may well be assumed, therefore, that bottle B is a full bottle, and that bottle C is also a full bottle. Bottle A is an empty bottle which is being put into the rack for collection by the milk man. It might be stated, however, that it is not absolutely essential to use three bottles. In fact, the understanding of the operation may be simplified, 55 to a certain extent, by simply visualizing the action of the two bottles A and B in Figure 1. Assuming, then, that B is a full bottle, it is locked immovably by the clamping star-wheels 22 which 60 partially embrace the neck thereof, as shown in dotted lines in Figure 4. The star-wheels are prevented from rotation in that the lugs on the periphery thereof are in engagement with the stop shoulders 40, on the trip bars 36. Now, 65 then, in order to remove this bottle B, it is necessary to tilt or swing the shoulders 40 down below the level of the rotary star-wheels 22, as indicated for example in dotted lines in Figure 5. This lifting action is accomplished by the rotation 70 of the star-wheels 23 and the coming into 75

engagement of the cam surfaces 29' and 35. Before the star-wheels 23 may rotate, however, it is necessary to release them by lifting the latches 29. Thus, to do this, we put a bottle in the right hand end through the entrance, as indicated at 5 A in Figure 1. As the bottle goes in, it rides underneath the plate 33 and lifts the plate up. The plate in turn rides underneath the lifting finger 30 causing the latches 29 to swing up above the level of the star-wheels 23. Now, the 10 star-wheels are free to rotate. As the bottle is shoved in, it comes into contact with the lugs 28 and starts the star-wheels to rotate. As the wheels rotate outwardly in opposite directions, as indicated in Figure 3 by arrows, the cam 15 edges 29' come underneath the cam edges 35, and this obviously lifts the right ends of said latch bars 36. At the same time, it swings the opposite shoulder ends 40 down allowing the star-wheels 22 to turn. Thus, by inserting the hand 20 in the chamber 12 and catching hold of the bottle B, it may be released from the rack and thereafter lifted up and removed for use. Manifestly, therefore, in order to get out the full bottle, it 25 serves the purposes of both the housewife and the dairy, as is obvious.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within 35 the field of invention claimed may be resorted to if desired.

I claim:

1. In a structure of the class described, a casing, a bottle slideway in said casing, a pair of 40 opposed pivotally mounted horizontally arranged star-wheels supported at a predetermined point above said slideway, pivoted trip members for said star-wheels, additional star-wheels for operating the trip members, and bottle actuated release means for the additional star-wheels. 45

2. In a structure of the class described, a casing, a pair of spaced parallel horizontally disposed angle irons supported in said casing to permit passage therebetween of the progressively moved milk bottles, said angle irons being provided with slots, inner and outer pairs of rotatably mounted star-wheels mounted on the angle irons and cooperable with the slots, trip means engageable with the inner star-wheels to prevent rotation thereof, said trip means being associated with the remaining star-wheels so that when the latter star-wheels are rotated the trip means is released to disengage and release the first-named star-wheels. 50 55

3. In a structure of the class described, a casing, a bottle slideway in said casing, bottle retaining means supported above said slideway, trip means associated therewith, a pair of star-wheels engageable with the trip means for actuating the trip means when the star wheels are moved by a bottle, retaining latches engageable with said star-wheels to prevent rotation thereof, and bottle actuated lifting means for said latches. 60 65

4. In a structure of the class described, a casing, a rack in said casing, said rack including a channeled slideway for the bottle, further including uprights and horizontal angle irons supported on said uprights, said horizontal angle irons having their vertical flanges arranged in 70 75

opposed parallel alignment and formed with slots, a pair of inner star-wheels mounted on the angle irons for rotation through said adjacent slots, a second pair of star-wheels pivotally mounted on the angle irons for rotation through the remaining slots, and a pair of pivoted trip bars on said angle irons, said trip bars being provided at corresponding ends with stop shoulders with which the first-named star-wheels engage, said

trip bars being provided at their opposite ends with cam elements with which the remaining star-wheels engage for lifting purposes, latches pivotally mounted on the angle irons to hold the last-named star-wheels normally against rotation, and pivoted latch operating means controlled by the insertion of a bottle in the manner and for the purposes described. 5
